UNITED STATES PATENT OFFICE.

HARRY S. HASKINS, OF PHILADELPHIA, PENNSYLVANIA, ASSIGNOR TO
EDWIN HARRINGTON & SON, OF SAME PLACE.

HOISTING-MACHINE.

SPECIFICATION forming part of Letters Patent No. 272,439, dated February 20, 1883.

Application filed December 14, 1882. (No model.)

To all whom it may concern:

Be it known that I, HARRY S. HASKINS, of the city and county of Philadelphia, and State of Pennsylvania, have invented an Improvement in Hoisting-Machines, of which the following is a specification.

My invention has reference to hoisting-machines adapted to be shifted from one position to another and arranged to run upon suitable rails; and it consists in providing the flanges of the wheels on the travelers with gear-teeth, and gearing therewith one or more pinions adapted to be revolved by an endless chain and chain-wheel to cause said traveler to move upon its rails and convey the hoisting apparatus with or without its load from one place to another, and in details of construction, as more fully set out in the following specification and shown in the accompanying drawings, which form part thereof.

Heretofore in hoists of this class the travelers have been caused to travel by simply pulling or pushing upon the hoist or its load, and a great deal of power and labor was expended uselessly in overcoming the inertia, and when a heavy load was upon the hoist it was necessary to have two or more men to move it.

The object of my invention is to provide suitable and cheap means, whereby one man with ease may cause the traveler to move along the rail and convey its load wherever desired.

In the drawings, Figure 1 is a side elevation of a traveler for hoists embodying my improvements. Fig. 2 is a plan view of same. Fig. 3 is a cross-section of same on line $\alpha\alpha$, and Fig. 4 is a cross-section of a modified form of traveler.

A is the traveler-frame, and B are its grooved supporting rollers or wheels, and run upon the overhead track D. The frame B is kept in position on the rails by lug E, and is provided on the bottom with a hole or ring, F, through which the hook of the hoist is passed. If desired, the hoist may be made integral with the traveler, though I prefer to make them separate. One or more flanges, C, of the supporting-wheels are made with teeth, and are geared with the pinion I upon the shaft H, supported

in a bearing, G, secured to the frame A. A chain-wheel, J, is secured upon the outer end 50 of shaft H, and an endless chain, K, passes over it, and is used to rotate the pinion I to cause the traveler to move upon its track in either direction. When the track is an I-beam two or four rollers or supporting-wheels may 55 be used in the manner shown in Fig. 4.

In place of making the flanges of the wheels toothed, I may provide suitable gear-wheels.

I do not limit myself to the construction of the devices shown, as they may be modified in 6c various ways without departing from my invention.

Having now described my invention, what I claim as new, and desire to secure by Letters Patent, is—

1. In a hoisting-machine, a traveler having a support at the bottom and below the center of gravity of the said traveler for the hoisting apparatus, supported upon wheels and adapted to run upon a track, provided with gearing arranged to cause said supporting-wheels having an independent axle to rotate, and a chain-wheel and chain to put said gearing in action, substantially as and for the purpose specified.

2. In a hoisting-machine, a traveler supported upon flanged wheels, one or more of said flanges being provided with teeth, in combination with gearing carried by said traveler and adapted to mesh with said toothed flanges, and a chain and chain-wheel to rotate said pinion, substantially as and for the purpose specified.

3. In a hoisting-machine, a traveler supported upon two or more toothed flanged wheels and adapted to run upon a track, in combination with a pinion gearing into two or more of said toothed flanges, and a chain-wheel and chain to rotate said pinion, substantially as and for the purpose specified.

In testimony of which invention I hereunto set my hand.

HARRY S. HASKINS.
